COCKTAIL SHAKER

Ralph N. Kircher, West Bend, Wis., assignor to
 West Bend Aluminum Company, West Bend,
 Wis., a corporation of Wisconsin

Application September 24, 1934, Serial No. 745,236

5 Claims. (Cl. 220—1)

This invention relates to an improvement in cocktail shakers.

One of the principal objects of the present invention is to provide a cocktail shaker which is designed for the thorough and expeditious mixing of iced or chilled drinks and which nevertheless, may be conveniently and comfortably manipulated or shaken without the drink mixer or bartender chilling his hands or employing a towel or some similar means to prevent the undesirable chilling.

Another object of the invention is to provide a cocktail shaker having these advantages and which is highly ornamental in appearance, well balanced and easily handled, readily and effectively sealed or opened up to dispense a drink, and yet of simple and durable construction and capable of being economically produced by manufacturing facilities and from materials readily available.

Other objects and advantages reside in certain novel features of the construction, arrangement and combination of parts which will be herein-after more fully described and particularly pointed out in the appended claims, reference being had to the accompanying drawing, forming a part of this specification, and in which:

Figure 1 is a view partly in side elevation and partly in transverse vertical section showing a cocktail shaker embodying the present invention;

Figure 2 is a view in horizontal section taken on line 2—2 of Figure 1; and

Figure 3 is a view in plan of the lower end cap, the same being viewed from line 3—3 of Figure 2 but the body or shell of the shaker being omitted.

Referring to the drawing, and more particularly to Figure 1, the numeral 1 designates generally the body or shell of the shaker which preferably consists of a drawn metal shell, the shell being drawn from a sheet of copper or other suitable metal and being suitably plated, as, for example, chromium plated. The body portion of the shell has an integral body 2 and at its upper end has a reduced neck 3 which is internally threaded as at 4 and provided with an outturned terminal flange 5.

For the base of the shaker a lower end cap designated at 6 is provided and preferably is molded from bakelite or other suitable composition. The end cap 6 has a flat bottom plate 7 and an annular peripheral flange 8 which partially telescopes over the lower end of the body of the shaker. Bosses 9 are integrally formed with the interior of the base 7 of the lower end

cap and are apertured to permit of the use of the screws 10 countersunk in the cap 6 and threaded into nuts 11 welded or soldered to the bottom 2 of the body of the shaker.

A removable upper end cap 15 is provided and is also molded from bakelite or other suitable composition. The properties that are essential in the composition are that caps 6 and 15 be sufficiently strong and rigid and also capable of resisting or retarding the exchange of heat, that is, the material of which these caps are composed must be of low heat conductivity. The body portion 16 of the upper end cap 15 has an outer peripheral outer flange 17. It also has a central opening 18 and around the margin of this opening 18 an integral upwardly extending annular flange 19 is provided. Likewise around the margin of its opening 18 a downwardly extending marginal flange 21 is formed. Between opposed portions of this flange 21 a number of spaced grids or bars 22 extend and are molded integral with the flange 21 to provide a strainer. In addition to the flange 21, a third flange 23 is integrally molded with the upper cap 15 and is located just outside of the flange 21 and in spaced relation to the flange 17. The exterior of this flange 23 is formed with threads 24 of a formation corresponding to the threads 4 and interengageable therewith in the assembly to mechanically and releasably interconnect the upper end cap and the shell or body portion of the shaker. In the space between the flanges 23 and 17 and above the threads 24, a washer or gasket 25 is provided and when the upper cap 15 is in place this washer is compressed against the flange 5 to provide an effective seal.

A closure 30 is provided for the opening 17 and preferably is in the form of an inverted cup to which an ornamental handle or finger piece 31 is attached. The body of the cup 30 is tapered in a manner corresponding to the tapered formation of the opening 17 and of the interior surface of the flange 20. Further, as the exterior surface of the body of the cup 30 and the surface of opening 18 and of flange 20 are smooth, when the cup 30 is in the position shown in Figure 1, these surfaces are snugly and frictionally engaged to hold the parts together and also to provide a seal therebetween.

When the closure 30 is removed it may be turned over to provide a jigger for measuring the amount of the alcoholic base of the drink.

In mixing a drink, the upper cap 15 is first removed and the ingredients placed in the body portion of the shaker, the closure 30 being uti-

lized if desired and, as pointed out, for the purpose of measuring the amount of alcoholic or flavoring ingredients. The closure 39 may then be put in the position shown in Figure 1 and the 5 end cap screwed into place. The operator then grasps the end cups, placing his fingers over the part 34 of the closure 39 and shakes the entire device up and down until the contents have been 10 appropriately agitated and chilled. The metal shell or body of the shaker will sweat and give the cold appetizing appearance that is desired but the drink mixer will not have his hands chilled since they are protected by the insulated end caps. When the shaking has been completed 15 the closure 39 is removed and the drinks poured directly into the cocktail glasses.

While I have shown and described one construction in which the invention may be advantageously embodied, it is to be understood that 20 this construction has been selected merely for the purpose of illustration or example and that various changes in the size, shape and arrangement of the parts may be made without departing from the spirit of the invention or the scope of 25 the subjoined claims.

The invention claimed is:

1. A device of the character described comprising a shell-like metallic container and caps of insulating material associated with the ends of 30 the container and designed to be grasped by the hands, one of said end caps being removable and having an opening therein provided with a strainer, and a removable closure for said opening.
2. A device of the character described comprising a cylindrical metal container having a closed bottom and provided with a reduced neck at its 35 upper end, said neck defining an opening into the container, a bottom end cap of flanged formation

fitted over the bottom of the container and secured thereto, and a removable top cap adapted to be interthreaded with the neck, said caps being of insulating material so that iced drinks may be mixed and agitated without chilling the hands. 5

3. A device of the character described comprising a cylindrical metal container having a closed bottom and provided with a reduced neck at its 10 upper end, said neck defining an opening into the container, a bottom end cap of flanged formation fitted over the bottom of the container and secured thereto, a removable top cap adapted to be interthreaded with the neck, said caps being of insulating material so that iced drinks may be mixed and agitated without chilling the hands, 15 said top cap having an opening, and a removable closure for said opening.

4. A device of the character described comprising a cylindrical metal container having a closed bottom and provided with a reduced neck at its 20 upper end, said neck defining an opening into the container, a bottom end cap of flanged formation fitted over the bottom of the container and secured thereto, and a removable top cap adapted to be interthreaded with the neck, said 25 caps being of insulating material so that iced drinks may be mixed and agitated without chilling the hands, said neck having a flanged seat, said cap having a recess provided with a gasket engageable with said flanged seat when the cap 30 is applied.

5. A cocktail shaker comprising a shell-like metallic container and end caps fitted over the ends of the container and designed to be grasped by the hand, said caps being of insulating material 35 so that iced drinks may be mixed and agitated without chilling the hands, one of said caps being removable.

RALPH N. KIRCHER.
